CLAIM

We claim the ornamental design for a toilet, as shown and described.

DESCRIPTION

FIG. 1 is a perspective view of an embodiment of the claimed design;

FIG. 2 is a left side plan view of the design shown in FIG. 1;

FIG. 3 is a right side plan view of the design shown in FIG. 1;

FIG. 4 is a front plan view of the design shown in FIG. 1; FIG. 5 is a rear plan view of the design shown in FIG. 1; FIG. 6 is a top plan view of the design shown in FIG. 1; and, FIG. 7 is a bottom plan view of the design shown in FIG. 1. The ornamental design which is claimed is shown in solid lines in the drawings. The broken lines in the drawings are for illustrative purposes only and form no part of the claimed design. Broken lines formed by equal length dashes show unclaimed portions of the design. Broken lines formed of unequal length dashes (i.e., dash-dot) show boundaries between claimed and unclaimed portions of the design.
